LUMINESCENT SIGN

Solomon L. Goldberg, New York, N. Y., assignor
to Floray Corporation, Dallas, Tex., a corpora-
tion of Texas

Application January 21, 1941, Serial No. 375,328

4 Claims. (Cl. 40—130)

The present invention relates to luminescent signs of the type comprising characters in the form of translucent gas-filled envelopes such as glass tubing or the like. More particularly, this invention is concerned with the utilization of electrodeless characters in association with an energizing field produced by a high frequency electrical source.

It is the primary object of the present invention to devise a sign or display device of the type just mentioned in which a plurality of individual characters such as letters or symbols may be arranged and rearranged conveniently and quickly to form any one of a variety of luminous wordings or picturizations.

It has been proposed heretofore to energize gas-filled tubes by placing them adjacent a series of conducting wires or in proximity to a conducting plate, and it likewise is old to construct a sign of luminous letters or symbols that are individually detachable and replaceable. However, due to defective construction and arrangement of parts, such signs have not been marketed successfully. In one old type of proposed sign the individual letter or symbol blocks—whether electrodeless or not—have themselves been provided with plugs or attachment elements requiring that they be mounted in definitely predetermined positions. In another type, embodying several proposed variations in design, electrodeless characters have been so arranged within a field produced by high frequency energization that they either light up non-uniformly, or weaken too rapidly in degree of luminosity, or are subject to both of these disadvantages.

In the present invention, on the other hand, a construction and arrangement of parts is provided wherein numerous individual letter or symbol characters may be interchanged and repositioned freely in an infinite number of positions simply by sliding them to and fro within a field charged by a high frequency source, while providing uniform and maximum luminescence for each gas-filled electrodeless envelope and without rapid deterioration of the envelopes which form parts of the characters.

One important feature of my invention resides in the novel construction of the character itself, and henceforth it follows that this improvement is an object of my invention. Briefly, this improvement consists in a simple but effective mounting of the letter or symbol upon an individual block that may be shifted readily to an infinite number of positions.

A further major object of the present inven-

tion resides in a system of parallel energized conducting strips, so interconnected, and arranged in such manner relative to gas-filled envelopes in an adjacent field that the envelopes are illuminated uniformly, individually and with respect to each other.

It is another important object of this invention to devise, in apparatus of the character above discussed embodying a high frequency source and

10 a panel-mounted conducting strip arrangement for creating an energizing field for luminescent elements, an improved set of electrical connections between the high frequency source and the strip arrangement.

15 There is yet another major object of my invention, consisting in the provision of an improved supporting and energizing structure for luminescent characters. More specifically, this object is accomplished through the use of a pair of parallel dielectric plates between which is disposed a plurality of energizing strips, one of the plates carrying a supporting member for luminescent characters, and all of the parts (excepting the freely movable characters) being held together by common fastening elements.

20 The foregoing objects, and other important and subordinate objects of the present invention should clearly appear from a study of the following detailed description when taken in conjunction with the accompanying drawings and the appended claims.

In the drawings:

Fig. 1 is a perspective view of a preferred form of the entire apparatus of the present invention, as it might appear for example when set up in a store window for advertising purposes.

Fig. 2 is a perspective view of an individual dielectric block carrying a luminescent tube for use in the apparatus seen in Fig. 1.

40 Fig. 3 represent a sectional view, taken substantially on the plane of line 3—3 in Fig. 2.

Fig. 4 is a view looking towards the front face of the apparatus of Fig. 1, with the panel structure removed to show the electrical parts assembly that energizes the conducting strips.

Fig. 5 is a cross section taken substantially along the plane of line 5—5 in Fig. 4.

Fig. 6 is a perspective view looking outwardly from the electrical system towards the front 50 panel structure to show the improved arrangement for connecting said system to the conducting strips.

Fig. 7 is a rear view of one of the panel elements and the conducting strips supported thereby, as would be seen when looking in the

direction of the arrows upon the plane of line 1-7 in Fig. 5.

Fig. 8 is a circuit diagram illustrating one preferred arrangement for energizing the conducting strips with high frequency current.

With continued reference to the drawings, wherein like numerals are employed to designate like parts, the disclosed apparatus includes a mounting and concealing structure comprising, essentially, a main housing 10 forming a central 10 box for reception of certain electrical parts and having a pair of integral wings 11 which extend to the right and left of itself. This unit is equipped with ventilating louvres, as shown, and is nicely decorated on its outer surfaces. Its only 15 novelty, however, is thought to reside in sufficient depth of the wings 11 to present air spaces without which there would be electrical power losses from the energized strips (yet to be described) to the apparatus contained by the main housing 10, and to avoid electrical disturbances that might in several ways unbalance the even distribution of energy to the gas-filled elements that are constructed for facile rearrangement into many different positions. It is understood, 25 of course, that the unit 10, 11, is formed of thin sheet steel or other suitable metal, for otherwise this problem would not be presented.

The housing structure is shaped to present a forwardly facing continuous flange 12 to which 30 the panel structure, or sign proper, is secured. The panel structure comprises a dielectric back plate 13 and a similar dielectric front plate 14, between which there is a set of horizontally arranged parallel strips of conducting ribbon 15, the latter being tacked or otherwise attached to the plate 13. These plates may be formed of "Masonite" or other suitable material, and the front plate preferably is given a glossy or decorative coating 16. This rectangular panel structure is surrounded by a rectangular frame 17, which except at its bottom edge is flanged at the front face, as shown at 18, 20. The fourth side of the frame 17 is completed by a separate horizontal strip of metal 21, shaped to afford a supporting ledge 22 for luminescent characters yet to be described. This panel structure and frame assemblage is united to the flanges 12 by screws 23, or any equivalent elements. Prior, however, to attachment of the assemblage to the main 50 housing, the panel structure is made in effect a one-piece unit, as follows.

After tacking or cementing the thin metal ribbons 15 to the plate 13, the two plates 13 and 14 are brought into coincidence and secured 55 tightly together by several screws 24 which pass through them and partially into a horizontal strip 25, of wood or the like, that engages the plate surface 16 to form a second ledge for supporting a second row of letters or symbols. Two 60 pairs of vertically offset holes 27 are drilled through or otherwise formed in the back plate 13. Now, or just prior to the last operation, into these holes are inserted the four horizontal legs of a pair of relatively rigid U-shaped conducting bars 26. The holes, it will be perceived, are directly behind certain of the metal ribbons 15, so that upon running sufficient solder 28 into the holes to fill the latter and surround the legs of the bars 26, the bars are electrically connected 70 to four of the ribbons and simultaneously firmly anchored to the panel structure. Wires 30 are connected to the bars 26 for subsequent connection to a source of high frequency current.

Now, by simply sliding the panel structure 75

into the three sided portion of the frame 17, adding the bottom 21 of the frame and uniting this assemblage to the flanges 12, the front face of the sign is complete and ready for reception of a plurality of luminous characters such as those seen in Figs. 1, 2, 3 and 5. The characters may comprise words or symbols but for most practical purposes consist of individual letter units that may be transposed and arranged to spell out words or sentences. Each preferably is constructed as follows.

A flat block 31 of dielectric material such as hardened plastic, of a thickness causing it to fit either of the ledges 22, 25 rather snugly so that its flat back will make contact with the plate 14, is provided with one or more holes 32 (normally two). A letter in the form of a gas-filled sealed tube 33 is shaped and designed for attachment to this block. The tube may be of transparent or translucent glass or similar material and its contained gas may consist of any of those commonly used or usable in signs of this type. The letter has one or more rearwardly offset projections 34, of a length slightly less than or approximately equal to the depth of the holes 32 and usually corresponding in number to the latter. These projections are sealed prongs at the top and bottom of the letter and each preferably hollow for a portion of its length so as to bring the gas into relatively close proximity to the metal ribbons 15 and thus utilize the field of greatest intensity for promotion of luminescence. In this manner better illumination can be obtained and any dark metallic deposits from the gases can be concentrated to a large extent within the non-visible prongs 34.

Each letter 33 is attached permanently to its supporting block 31 by partially filling the holes 32 with a hardening cement 35 prior to insertion of the prongs 34. In addition, a transparent cement 36 may be placed at various points where the letter contacts the block. The characters thus formed may be arranged readily, within the economical limitation of a few dozen units, to spell out various words and groups of words. For example, a small sign within a shop window may be rearranged frequently—something that is impossible without relatively great expense at the present time. It will be understood, however, that this invention is not limited to the field of small signs, but may be adopted in very large frequently modified signs such as those used on theatre fronts and the like.

The arrangement of the metallic ribbons or strips 15 is quite important. Obviously, it may be carried forward into a system embodying three or more rows of characters, but basically it is constituted as follows. Each row of characters is energized by a plurality of strips—preferably three—and two of these strips are interconnected electrically, as at 37 by wire or a short piece of conducting ribbon. Thus there are formed at least two pairs of joined strips and at least two single strips. The two pairs of joined strips are connected to each other and to one side of the energizing line by one of the bars 26, and the two single strips are conjointly connected to the other side of the line. Although this arrangement is not essential to produce fairly satisfactory luminescence of the tubes it has proven superior, by prolonged trial and experimentation, to any other arrangement tried by the applicant. Such matters cannot be worked out by theory alone.

There are, perhaps, numerous circuits that can be utilized to provide the necessary high fre-

quency current required to energize the sets of strips 15. A very satisfactory circuit, built as a unit to be inserted through the rear side of the housing and connected to the bars 26, is as follows. A pair of conventional lead wires 40, 41, as from the usual 110 v. source, are connected through a transformer T to an oscillating tube O and a coil C. The terminals 30 of the coil C are disposed adjacent the bars 26 and connected thereto as previously described. The transformer T comprises a primary winding p and two secondaries s₁ and s₂, as shown. The secondary s₁ produces a high voltage of, say, 300 v. or more and is connected to the plate of the tube and through a choke c₁ and a condenser c₂ to two intermediate portions of the coil C, as indicated. The secondary s₂, of much lower voltage, is connected to the filament of the tube O and thence to another intermediate portion of the coil C. The grid of the triode tube O is connected as shown, through a grid leak GL to one of the terminals 30 of the coil C. This arrangement supplies uniform energization to the wires 30 and hence maintains substantially invariable current and voltage within the set of strips 16.

It should be understood that the present invention is not circumscribed by the specific illustrations and the detailed description, but that numerous changes may be made within the scope and spirit of the invention. Many alterations and equivalents will be obvious to those skilled in the art and therefore I wish to be limited, as is customary, only by those restrictions which necessarily must be read into the appended claims in view of the prior art.

What is claimed is:

1. A display unit or panel structure for luminescent signs comprising a pair of dielectric panels disposed back to back with a flat electrical conducting means therebetween, means fastening said conducting means to one of said panels, a

strip for supporting the luminescent characters adjacent the display side of the unit, and means projected through the front panel and joining said strip to the back panel to thus unite the four enumerated parts and closely confine said conducting means.

2. In the structure defined in claim 1, said panels being rectangular, a three-sided frame designed to slidably receive the edges of the united panels, and a rigid strip designed to form the fourth side of the frame and to provide another support for luminescent characters.

3. An energizing device for luminescent signs, comprising a dielectric panel having at least four spaced conducting strips attached to one face thereof, at least four apertures extending through the panel at points directly behind said strips, a pair of relatively stiff substantially U-shaped connecting elements arranged at the rear face of the panel with their legs projected into said apertures, and chunks of soldering material substantially filling said apertures and uniting said legs to said strips.

4. A luminescent sign comprising a metal box having a central housing provided with offset wings, the housing and wings designed to afford a front opening for the box, a display panel structure closing said opening and comprising a pair of dielectric panels separated by an energizing device designed to illuminate any gas-filled tubing disposed at the front face of the structure, high frequency electrical apparatus mounted within said central housing and having direct forward connections through the rear panel to said energizing device, said wings having sufficient depth to form air gaps between the panel structure and the rear side of the box, and said energizing device being so constructed and arranged as to be spaced inwardly from all edges of said front opening of the box.

SOLOMON L. GOLDBERG.
